(57) **CLAIM**

The ornamental design for a harness plug, as shown and
described.

DESCRIPTION

FIG. 1 is a first perspective view of a tool-side harness plug
according to a first embodiment.

FIG. 2 is a front side view of the tool-side harness plug of
FIG. 1.

FIG. 3 is a first perspective view of a tool-side harness plug
according to a second embodiment; and,

FIG. 4 is a front side view of the tool-side harness plug of
FIG. 3.

The broken lines in the drawing are for the purpose of
illustrating a portions of the article that form no part of the
claimed design.

1 Claim, 4 Drawing Sheets
